UNITED STATES PATENT OFFICE.

WALTER F. HEROLD, OF NEWARK, NEW JERSEY, ASSIGNOR TO THE BASSICK COMPANY, OF BRIDGEPORT, CONNECTICUT, A CORPORATION OF CONNECTICUT.

CASTER.

Application filed May 18, 1922. Serial No. 561,794.

To all whom it may concern:

Be it known that I, WALTER F. HEROLD, a citizen of the United States, and resident of Newark, in the county of Essex and State 5 of New Jersey, have invented certain new and useful Improvements in Casters, of which the following is a specification.

The invention relates to casters and particularly to casters which are adapted to 10 support furniture or other objects having angle iron or similar flanged legs or portions to which a caster may be applied. The term "caster" is used herein broadly to include furniture slides and the like furniture 15 supporting members.

An object of the present invention is the provision of a simple and effective construction of the character referred to. In accordance with the invention a member is provided 20 in which the lower end of an angle iron or similar flanged leg or portion of an object to be supported is received. An element of the caster or furniture support is inserted within the receiving member between 25 a wall of the same and a surface of the angle iron, the parts coacting in such a manner as to bind them together.

In one form of my construction a member is provided having flanges which embrace 30 the two legs of an angle iron when the latter is inserted therein, this member having a portion which connects the flanges thereof which extend adjacent to the inner faces of the angle iron. The element of the caster, 35 such as a pintle receiving socket, is driven into the space between the connecting portion of the receiving member referred to and the inner faces of the angle iron. The parts are correspondingly tapered so that 40 when the caster element is forced into position this element, the receiving member and the angle iron, will be firmly bound together. The weight of the furniture or article supported will be transmitted directly from the 45 angle iron through its receiving member to the caster element. Such a construction may be manufactured simply and cheaply and may be installed with a minimum of time and skill.

50 Other objects of the invention relate to the provision of improved combinations of parts and details of construction, all as will be more fully described hereinafter.

In order that the invention may be more 55 clearly understood attention is hereby di-

rected to the accompanying drawings forming part of this application and illustrating certain embodiments of the invention. In the drawings—

Fig. 1 represents a side elevation of a 60 caster construction applied to the lower end of an angle iron leg;

Fig. 2 is a vertical section taken on line 2—2 of Fig. 1, the caster pintle being shown 65 in front elevation;

Fig. 3 is a horizontal section taken on line 3—3 of Fig. 1;

Fig. 4 is a perspective view of the bracket or angle iron receiving member shown in the preceding figures;

Fig. 5 is a plan view of a blank from 70 which the receiving member shown in Fig. 4 may be formed;

Figs. 6 and 7 are respectively side and 75 end elevations of a cylindrical member formed from the blank shown in Fig. 5, illustrating a step in the production of the receiving member;

Fig. 8 is a plan view of a blank from 80 which a modified form of receiving member may be made;

Fig. 9 is a perspective view of a receiving member formed from the blank shown in Fig. 8;

Fig. 10 is a plan view of a blank from 85 which another form of receiving member may be made, and

Fig. 11 is a perspective view of a form 90 of receiving member made from the blank shown in Fig. 10.

Referring to the drawings, the lower end portion of an angle iron is shown as having legs or flanges 1, 2. This angle iron may comprise a leg or other element of an article of furniture or other object to be 95 supported. The lower end of the angle iron is inserted into a receiving member, one form of which, illustrated in Figs. 1 to 4, is indicated generally by the reference character 3. Member 3 is shown in reversed position in Fig. 4, in order that the construction may be clearly shown.

Member 3 is preferably formed of sheet metal and is pressed or otherwise formed to provide portions 4, 4, which extend at 105 right angles to each other from the corner or angle 4¹.

The metal at the outer ends of flanges 4, 4, is curved inwardly as shown at 5, 5, flanges 6, 6, each extending parallel to one 110

of the flanges 4 for a distance from the curved portion 5. The inner ends of flanges 6, 6, are joined by a connecting portion 7 which is preferably curved outwardly about 5 an arc of a circle.

The angle iron 1, 2, may be inserted into member 3 with the legs of the angle iron extending loosely between parallel flanges 4, 6, of the receiving member and with the angle or corner 8 of the angle iron received within the angle 4¹ of the receiving member. The receiving member is preferably provided with a pair of lugs or straps 9, 9, each of which extends horizontally from one of the portions 4 of the member across the space between the portion 4 and the portion 6 parallel thereto. These lugs will constitute seats upon which the lower ends of the legs of the angle iron will rest. These lugs are preferably formed with end portions 10 which are bent up and pressed against the outer surfaces of flanges 6 of the member.

A vertical element of the caster or furniture supporting member may be forced upwardly into place between wall 7 of member 3 and the inner faces of the angle iron. This vertical caster element may and preferably does take the form of a pintle socket or sleeve 11, having a bead or flange 12 at its lower end. Preferably this socket will be driven into position with a forced fit so that it will press the legs of the angle iron firmly against the outer flanges 4, 4, of the receiving member and will itself bind firmly against the inner faces of the angle iron, and the inner surface of the connecting portion 7 of member 3. Preferably socket 11 and portion 7 of the receiving member are provided with a corresponding slight taper. The socket may be driven into position as far as it will go in which position the flange or bead 12 at the bottom of the socket will abut against the lower edges of portions 4 and 7 of the receiving member and against the lower edges of the legs of the angle iron.

In the construction shown socket 11 is of the top bearing type and is provided with an arched closure 13 at its upper end, it being understood, however, that the invention is not limited to this construction.

With such a construction the pintle socket is firmly secured in position within the angle of the angle iron and a caster may be applied thereto whenever desired by inserting the pintle of the caster within the socket. In the construction shown in Figs. 1 and 2 of the drawings, a caster is shown having the usual caster wheel 14 carried by the horn 15, the pintle 16 being secured to the transverse top portion of the horn and extending vertically upwards therefrom. Any desired means may be employed for holding the pintle frictionally within the

socket. In the drawings I have shown a spring ring 17 mounted within a peripheral slot 18 in the pintle for this purpose.

The member 3 may be formed as an integral construction from a circular blank 3¹ having a central opening 19 therethrough and having a pair of ears 9¹ extending radially from points which may be positioned 90° apart about the periphery of the blank. Blank 3¹ may be worked by well known means into the cylinder shown at 3^a in Figs. 6 and 7 having ears 9¹ extending from points 90° apart at one end of the cylinder. The cylinder may then be pressed by suitable mechanism into the form shown in Fig. 4 and the ears bent over to form the lugs 9 as shown.

A similar receiving socket may be formed from the blank 3^b shown in Fig. 8 which comprises a rectangular strip with ears 9^b extending from one of the side edges. The opposite end edges of the blank are cut away to provide ears 20, 20, at one end and ears 21, 21, at the other end, the ears at each end being in alignment with cut out portions at the other end. This blank may be bent to form to provide the receiving member shown in Fig. 9, having the flanges 4^b, 4^b, 6^b, 6^b, and connecting portion 7^b corresponding to the portions 4, 4, 6, 6, and 7 of the construction shown in Fig. 4. The ears 9^b will be bent over to form supports for the lower end of the angle iron in the same manner as the lugs 9 in the form first described. The ears 20, 20, and 21, 21, at opposite ends of the blank will be pressed into position in the corresponding recesses at the opposite end of the blank. A firm connection may be made by pressing the ears firmly into position or by welding the joint, as desired.

A modified form of construction is shown in Fig. 11, which may be formed from a blank 3^c shown in Fig. 10. In this form of construction the complete flanges 4, or 4^b, of the first two forms of construction described are omitted, incomplete flanges 4^c being provided instead. With this construction one of the flanges 4^c is connected by the curved portion 5^c of the metal with the parallel flange 6^c which is joined by the curved connecting portion 7^c to the other flange 6^c which is joined by the other curved portion 5^c to the other partial rear flange 4^c. Flanges 4^c are provided with lugs 9^c which are bent across the opening between the lower edges of flanges 4^c and 6^c to form seats for the lower end of the angle iron in the manner already described. The blank 3^c is provided at its ends with ears 9^c which may be bent into position to form the lugs 9^c illustrated in Fig. 11. The manner in which blank 10 may be pressed to shape to form the member shown in Fig. 11 will be obvious. The lower end of an angle iron

1, 2, is shown in Fig. 11 as inserted in position with its legs extending between the parallel flanges 4^c and 6^c of the receiving member.

5 It will be understood that references to angle iron legs or members herein are to be understood as including similar flanged members.

It will be noted that the device described 10 may be used in connection with angle members having considerable variations in the thickness of the metal and the width of the flanges. It is not necessary that the legs of the angle iron should extend laterally 15 into contact with the closed end portions 5 of the receiving member, considerable variation in the width of the angle iron flanges being provided for. Likewise such variation as is encountered in commercial practice 20 in the thickness of the angle iron flanges will be provided for when the cylindrical caster element, such as the socket 11, shown, and the wall 7 of the receiving member are formed with slight tapers, as described. It 25 will likewise be noted that the construction does away with the need of employing screws or rivets, or other additional securing devices for securing the receiving member to the angle iron. This is a particular ad- 30 vantage because of the difficulty which might be encountered in properly aligning such openings in the receiving member and in various forms of angle iron with which the same might be used.

35 It should be understood that while I have described certain forms and features of the invention with particularity, the invention is not limited to the exact details which have been described, but that various modifications 40 may be employed as will be clear to those skilled in the art after reading this specification, the scope of the invention be-

ing indicated by the accompanying claims.

What I claim is:

1. In a caster, the combination of a member adapted to receive the lower end of an angle iron and a pintle sleeve adapted to be inserted and frictionally secured, with a forced fit, within said member between a surface thereof and the inner faces of the angle iron, said sleeve being adapted to press against said surface of the receiving member and a surface of the angle iron sufficiently to bind said member, sleeve, and angle iron together, said sleeve also having a closed top and acting as a pintle-receiving socket. 45

2. In a caster, the combination of a member adapted to receive the lower end of an angle iron, having portions between which the legs of the angle iron may be inserted and a connecting portion opposite the position occupied by the angle of the angle iron, and a vertical sleeve having a closed top adapted to be forced with a wedging action between said connecting portion and the inner faces of the angle iron, to bind the parts together, and to transmit the thrust of the weight carried by the angle iron to the supporting element of the caster. 60

3. In a caster, the combination of a socket member adapted to fit loosely upon the lower end of an angle iron, and a cylindrical caster sleeve adapted to be forced into place with a wedging action within said socket member and against a surface of the angle iron, to bind said member and angle iron together and to serve as a pintle-receiving sleeve. 65

In testimony whereof I have signed my name to this specification, at Bridgeport, Connecticut, on this 12th day of May, 1922. 70

WALTER F. HEROLD.
